UNITED STATES PATENT OFFICE.

JOHN ROBERT BURGESS, OF BROADHEATH, ENGLAND, ASSIGNOR TO LINOTYPE AND MACHINERY LIMITED, OF LONDON, ENGLAND.

DISTRIBUTING MECHANISM OF TYPOGRAPHICAL MACHINES.

1,119,495.

Specification of Letters Patent.

Patented Dec. 1, 1914.

Application filed August 4, 1914. Serial No. 854,912.

To all whom it may concern:

Be it known that I, JOHN ROBERT BURGESS, a subject of the King of the United Kingdom of Great Britain and Ireland, residing at Linotype and Machinery Works, Broadheath, in the county of Chester, England, have invented new and useful Improvements in or Relating to the Distributing Mechanism of Typographical Machines, 10 of which the following is a specification.

This invention relates to typographical machines such as those known under the trade mark "Linotype" and others of a kindred character and particularly to the devices known as separator boxes by which the successively leading matrices of a line or plurality of matrices descending by gravity down inclined guides, are, by a pair of vertically reciprocating dogs, separated from 15 the immediately following matrix preparatory to their being engaged by the distributor mechanism which delivers them each into its respective magazine channel. These dogs are usually reciprocated in alternation 20 by means of a cam fast on, or operatively connected to, one of the distributor screws, their reciprocations continuing throughout the period of rotation of the said distributor screw, and this quite irrespective of whether 25 30 or not there are any matrices to be acted upon by the dogs.

As a consequence of the above named continuity of reciprocation much needless wear and tear of the parts involved occurs, and 35 the object of the present invention is to overcome this difficulty by providing means whereby the said parts are retained out of operation when no matrices are to be separated by the dogs, and caused to come into 40 operation by matrices approaching those dogs.

It should be here explained that the above-mentioned separator boxes differ from the ordinary distributor lift boxes in respect of the fact that the matrices travel through the former by gravity, whereas in the latter, each line of matrices is moved along guide rails by a pusher, until the leading matrix reaches a stop, after which each 45 successively leading matrix is raised by a matrix lifter into engagement with the distributor screws. In connection with such distributor lift boxes, means have already been proposed for preventing the reciprocation of the matrix lifter, such means having

depended for their operation more or less directly upon the action of the above-mentioned pusher, which, so far as the present invention is concerned, may be entirely absent from the machine. According to the 60 present invention, the operation of the vertically reciprocating dogs is controlled by the matrices to be separated, quite irrespectively of the influence on the matrices of any other organ of the machine.

The invention will now be described by reference to the accompanying drawings, which are to be taken as part of this specification and read therewith.

In these drawings:—Figure 1 is a front elevation of a separator box provided with the present improvements and shown as detached from the typographical machine, and with a matrix passing through it, and Fig. 2 is an elevation of the same as seen from the 75 right hand side of Fig. 1.

1 is the front wall and 2 the back wall of the separator box which is of ordinary well known construction and which, when hereinafter referred to as a whole, is identified 80 by the numeral 1. The walls 1 and 2 are provided with the usual inwardly-facing, inclined guides 3 which serve as tracks along which the lugs of the matrices 4 travel during the descent of the latter to the vertically 85 reciprocating dogs 5, 6, these dogs serving, as ordinarily, to separate the successively leading matrices of the line which is, at the time, descending by gravity down those guides; this separation is a step preparatory 90 to the matrices being engaged by that part of the distributor mechanism which delivers them each to its respective magazine channel.

The last named part of the distributor 95 mechanism forms no part of the present invention, and consequently it has not been included in the accompanying drawings.

The dogs 5, 6, are reciprocated in alternation, as ordinarily, by means of a cam 7 and spring 8 acting antagonistically to each other, the said cam being rotated directly by one of the distributor screws or by other convenient means. The cam 7 acts upon a lever or arm 9 (hereinafter referred to as 105 the cam lever) and serves to move it in one direction, while the spring 8, attached to the said cam lever, serves to move it in the opposite direction and, during the operation 110 of the dogs 5, 6, to maintain the engagement

between that lever and the cam. The two dogs 5, 6, are both connected to the same lever or levers 10 which as ordinarily are rocked about the pivot 11 by the cam lever 9.

- 5 For the purpose of preventing the operation of the parts 5, 6, 9 and 10, in accordance with the present invention, there is provided a trigger, or detent 12 which is capable of engaging, as shown in full lines in Fig. 1, 10 with a stud or projection 13 on the cam lever 9, to hold that lever out of reach of the cam 7; this condition of engagement being that which obtains when there are no matrices to be acted upon by the dogs 5, 6, and consequently when there is no necessity for the latter to be operated. The trigger 12 is pivoted at 14 to the adjacent wall of the separator box 1 (it is the wall 2 in the example illustrated) and is provided with a tail 15 15 extending into the path of the descending matrices 4, and the weight of the said trigger and tail is so distributed as to present a preponderance on its lever-engaging end, this preponderance, however, is only such 20 that the weight of the lightest matrix will serve to tilt the trigger 12 and thereby cause it, as shown in dot-and-dash lines in Fig. 1, to release the cam lever 9 which thereafter, in the known manner, is reciprocated by the 25 cam 7 and spring 8, this operation continuing only so long as the oncoming matrices retain the trigger 12 out of engagement with the cam lever 9, the cessation of the supply of such matrices allowing the trigger to 30 again drop into engagement with the stud 13 and hold the cam lever 9 out of operative contact with the cam.

Having described my invention I declare that what I claim and desire to secure by 40 Letters Patent is:—

1. In a typographical machine, the combination with a separator box through which the matrices pass by gravity and separating dogs adapted to separate each successively leading matrix from the next following matrix, of means adapted to operate the separating dogs only when matrices are presented to them for separation.
2. In a typographical machine, the combination with a separator box through which the matrices pass by gravity and separating dogs adapted to separate each successively leading matrix from the next following matrix, of means adapted to prevent the operation of the separating dogs except when matrices are presented to them for separation.
3. In a typographical machine, the combination with a separator box through which the matrices pass by gravity and separating dogs adapted to separate each successively leading matrix from the next following matrix, of means controlled by the matrices adapted to prevent the operation of the separating dogs except when matrices are presented to them for separation.

4. In a typographical machine, the combination with a separator box, separating dogs adapted to separate each successively leading matrix from the next following matrix, and means adapted to operate the separating dogs, of a movable device actuated by the matrices and adapted to control the operation of the said means.

5. In a typographical machine, the combination with a separator box, separating dogs adapted to separate each successively leading matrix from the next following matrix, a cam and cam lever adapted to operate the separating dogs, and a spring adapted to maintain the cam lever in constant operative contact with the cam, of a movable device released by the matrices, adapted to hold the cam lever out of such operative contact when there are no matrices presented for separation.

6. In a typographical machine, the combination with a separator box, separating dogs adapted to separate each successively leading matrix from the next following matrix, a cam and cam lever adapted to operate the said dogs, and a spring adapted to maintain the cam lever in constant operative contact with the cam, of a stud on the said cam lever and a pivoted trigger released by the matrices, adapted to engage the said stud when there are no matrices presented for separation, and thereby hold the cam lever out of operative contact with the cam.

7. In a typographical machine, the combination with a separator box, separating dogs adapted to separate each successively leading matrix from the next following matrix, a cam and cam lever adapted to operate the said dogs, and a spring adapted to maintain the cam lever in constant operative contact with the cam, of a stud on the said cam lever, a pivoted trigger adapted to normally engage the stud to hold the cam lever out of operative contact with the cam, and a tail on the trigger extending into the path of the matrices moving toward the dogs and adapted to be depressed by those matrices to disengage the trigger from the stud.

8. In a typographical machine, the combination with a separator box, alternately reciprocating separating dogs adapted to separate each successively leading matrix from the next following matrix, a cam and cam lever adapted to simultaneously move the separating dogs in relatively opposite directions, and a spring adapted to maintain the cam lever in constant operative contact with the cam, of a movable device released by the matrices, adapted to prevent the operation of the separating dogs except when matrices are presented to them for separation.

9. In a typographical machine, the combination with a separator box through which the matrices pass by gravity, and means

adapted to separate each successively leading matrix from the next following one, of means to prevent the operation of the separating means except when matrices are presented for separation.

10. In a typographical machine, the combination with distributing mechanism and means for delivering the matrices individually thereto, of means for preventing the op-

eration of said delivery means, the said preventing means being controlled exclusively by the matrices.

In witness whereof I have hereunto set my hand in the presence of two witnesses.
